FOOD AND BEVERAGE SERVING SET

Maurice G. Mountain, Jr., and William S. Ripley, York,
Pa., assignors to Susquehanna Broadcasting Co., York,
Pa.

Filed Sept. 18, 1973, Ser. No. 398,475

Term of patent 14 years

Int. Cl. D7—99

U.S. Cl. D7—3

FIG.1

FIG.2

FIG. 1 is a top plan view of a food and beverage serving set showing our design.

FIG. 2 is a side elevation thereof.

FIG. 3 is an end elevational view as seen from the right of FIG. 1.

FIG. 4 is an end elevational view as seen from the left of FIG. 1.

FIG. 5 is a sectional view thereof taken on the line 5—5 of FIG. 1.

The food and beverage serving set comprising the design of the present invention consists of a tray having recesses complementary to and separately receiving the carafe and food cover which comprise part of the design.

We claim:

The ornamental design for a food and beverage serving set, substantially as shown and described.
